FIRE EXTINGUISHER

Filed March 22, 1928

UNITED STATES PATENT OFFICE

HOWARD WATERS DOUGHTY, OF AMHERST, MASSACHUSETTS

FIRE EXTINGUISHER

Application filed March 22, 1928. Serial No. 263,669.

This invention relates to fire extinguishers of the type which functions automatically to spray a fire-extinguishing liquid over surfaces in the vicinity of the extinguisher when 5 the temperature rises beyond a predetermined point.

Such extinguishers comprise an inner container, adapted to be filled with a fire-extinguishing liquid, such as carbon tetrachloride, and a surrounding receptacle for a liquid which upon heating releases a gas, thereby creating pressure whereby the fire-extinguishing liquid is ejected through a suitable outlet. A concentrated ammonia solution is a suitable gas-generating agent because when the solution is heated the ammonia gas becomes insoluble and pressure is developed with comparative rapidity.

The outlet from the extinguisher may be 20 closed normally by a frangible diaphragm of thin material such as metal foil which is ruptured when the pressure develops or a closure may be held in position to seal the outlet by a fusible link such as those used 25 in automatic sprinkler systems.

Both of the closures described are, however, subject to certain disadvantages. The metal foil may be punctured without actual bursting before the temperature has risen 30 sufficiently to develop the necessary pressure in the extinguisher. In this case the liquid may be discharged so slowly that it does not spread over the burning surface. If a fusible link is used to seal the extinguisher, the link 35 may be melted by local heating before the extinguisher has attained a temperature sufficient to generate gas therein. In that case the discharge may not be sufficiently rapid to accomplish the desired spreading of the 40 fire-extinguishing liquid. In either case the object is defeated or the operation made less effective.

It is the purpose of the present invention to provide a simple and effective fire extinguisher which avoids the difficulties mentioned and consequently affords assurance of the desired fire protection.

In carrying out the invention I employ an outer receptacle and inner container with an 50 outlet from the inner container as in similar

devices heretofore used. The outlet is closed by a stopple. A screw or equivalent means, mounted in a frame in which the outer receptacle of the extinguisher is supported, bears against the stopple which is thus firmly 55 and securely held against the outlet to seal the extinguisher. A lock nut may be provided on the screw to avoid accidental release of the stopple. Preferably the stopple is in the form of a spray head to direct the 60 liquid over the surrounding surface when it is released.

The outer receptacle of the extinguisher may be supported in the frame by a fusible member. The fusible member is inserted before the extinguisher is assembled and serves to hold the parts in assembled relation 65 against the pressure of the screw. The fusible member may be arranged to act against the screw in compression or in tension. 70

In preparing the extinguisher the stopple is removed and the air vent is opened. The gas-producing liquid, such as concentrated ammonia solution, is introduced through the outlet. The inner container is then filled 75 with the fire-extinguishing liquid to displace the gas-producing liquid which is forced into the outer receptacle. The fusible member is inserted in the frame with the outer receptacle of the extinguisher. The stopple is then 80 inserted in the outlet and is seated tightly by manipulating the screw.

The extinguisher is thus charged and remains unchanged until a fire occurs. The heating of the extinguisher causes the gas-producing liquid to release the gas and generate pressure. When the temperature has risen sufficiently to melt the fusible member, the latter fuses, thus permitting the extinguisher to drop slightly. The outlet is released from the stopple and the pressure forces the liquid from the inner container through the outlet. It is distributed over the surrounding surface by the spray head.

The composition used for the fusible member may be such as to permit release of the liquid only after sufficient pressure has developed in the outer receptacle by the heating of the extinguisher. Various alloys having suitable melting points to accomplish this purpose are 100

well known in the art. The melting of the fusible member ensures the separation of the outlet from the stopple because of the weight of the receptacle and its contents. The device 5 operates with certainty and provides adequate protection against fires in its vicinity.

The extinguisher will be further described with reference to the accompanying drawing, illustrating the preferred embodiment there- 10 of, in which

Fig. 1 is a vertical section through an ex-tinguisher embodying the invention;

Fig. 2 is a section on the line 2—2 of Fig. 1;

Fig. 3 is a vertical section through another 15 form of the device; and

Fig. 4 is a section on the line 4—4 of Fig. 3.

Referring to Figs. 1 and 2 of the drawing, an inner container 5 of glass, porcelain, aluminum or other non-corrodible material is enclosed within an outer receptacle 6 which is 20 made preferably of aluminum. The container 5 may rest on spacers 7 and is somewhat smaller than the receptacle 6 to afford space for the gas-producing liquid. A tube 8, also 25 preferably made of aluminum, extends from the bottom of the inner container through the top of the outer receptacle to provide an outlet. A removable cap 9 is provided on the outer receptacle to vent the air when the ex- 30 tinguisher is being filled.

A frame 10 of any suitable metal is provided with a bottom 11 having an opening 12 therein. A plug of fusible metal 13 rests on the bottom 11 with a projection extending into 35 the opening 12 to prevent displacement. A plate 14 rests on the fusible plug and supports the outer receptacle 6 of the extinguisher.

The frame is provided with a spacing ring 15 to prevent lateral displacement of the extinguisher and with a bail 16 hinged at 17 thereto. At the top of the bail is a threaded 40 opening to receive a screw 18. A spray head 19, preferably of glass, porcelain, or metal, is mounted on the screw and has a conical 45 stopple 20 thereon which engages the outlet end of the tube 8. The stopple may be held tightly in place to seal the extinguisher, the screw being locked by a nut 21. A ring 22 may be provided on the end of the screw to 50 facilitate suspension of the extinguisher.

As hereinbefore explained, when the extinguisher has been filled and adjusted, the melting of the plug will release the end of the outlet tube from the stopple and permit ejec- 55 tion of the fire-extinguishing liquid under pressure developed by the heating of the liquid in the outer receptacle. When the contents are discharged the extinguisher can be refilled and adjusted with a fresh fusible plug in the 60 frame for further use.

In Figs. 3 and 4 of the drawing a slightly different form of the invention is illustrated. An inner container 25 of glass, porcelain, aluminum or other non-corrodible material 65 is enclosed within an outer receptacle 26 which

is made preferably of aluminum. The container 25 may rest on spacers 27 and is smaller than the receptacle 26 to afford space for the gas-producing liquid. A tube 28, also pre- 70 ferably made of aluminum, extends from the bottom of the inner container through the top of the outer receptacle to provide an outlet. A removable cap 29 on the outer receptacle permits the venting of the air when the ex- 75 tinguisher is being filled.

The outer receptacle 26 is provided with a flange 30 near its upper end and the flange is supported upon an annulus 31 which in turn rests upon fusible plugs 32 supported on inwardly directed lugs 32' of a frame 33. The frame may have a threaded opening to receive a screw 34 which carries a stopple 35 which is adapted to cooperate with an outlet from the tube 28. A lock nut 36 on the screw can be used to lock the device when it has been 80 assembled. The screw may also carry a ring 37 whereby the extinguisher can be suspended. The stopple 35 is preferably in the form of a spray head to facilitate the distribution of the fire-extinguishing liquid.

The apparatus as described is filled with the gas-producing and fire-extinguishing liquid as in the preceding embodiment of the invention, and when so filled it remains unchanged until a fire occurs in the vicinity. When the temperature rises sufficiently the fusible plugs 32 are melted and the receptacle 26 is permitted to drop so that the outlet from the tube 28 is released from the stopple 35. The heating of the gas-producing liquid in the receptacle 26 causes the ejection of the fire-extinguishing liquid from the container 25 and the liquid is distributed over the surrounding surface to extinguish the fire.

Aluminum is preferably used for the outer receptacle because it is not attacked by carbon tetrachloride and ammonia solutions, whereas most other metals are easily corroded by these solutions. Moreover, aluminum is light in weight and can be shaped easily by drawing or otherwise. It presents an attractive appearance and can be finished by simple operations and at minimum expense.

Glass, porcelain and like materials are pre- 105 ferably employed for the inner container because of their low heat conductivity. Premature heating of the fire-extinguishing liquid is thus avoided. Aluminum can, however, be used.

The frame may be made of any suitable metal, such as iron, brass, or aluminum. It may be finished in any suitable manner to provide an attractive appearance.

Various changes may be made in the de- 110 tails of construction and arrangement of the parts without departing from the invention or sacrificing any of the advantages thereof.

I claim:

1. In a fire-extinguisher, inner and outer 115

receptacles, a tube extending from the inner receptacle through the wall of the outer receptacle, fusible means supporting the outer receptacle and means exerting pressure on the fusible means to positively seal the outlet from the tube while the fusible means is intact.

2. In a fire-extinguisher, inner and outer receptacles, a tube extending from the inner receptacle through the wall of the outer receptacle, fusible means supporting the outer receptacle and means exerting pressure on the fusible means to positively seal the outlet from the tube while the fusible means is intact, said means including a spray head.

3. In a fire-extinguisher, inner and outer receptacles, a tube extending from the inner receptacle through the wall of the outer receptacle and movable therewith, fusible means supporting the outer receptacle and threadedly supported means to positively seal the outlet from the tube when the fusible means is intact, said means being held against movement with the tube.

4. In a fire-extinguisher, inner and outer receptacles, a tube extending from the inner receptacle through the walls of the outer receptacle and movable therewith, a frame in which the extinguisher is mounted, means on the frame held against movement with said tube to engage and seal the outlet from the tube and a fusible plug on the bottom of the frame supporting the extinguisher in spaced relation thereto.

5. In a fire-extinguisher, inner and outer receptacles, a tube extending from the inner receptacle through the wall of the outer receptacle and movable therewith, a frame in which the extinguisher is mounted, means threadedly mounted on the frame and held against movement with said tube to engage and seal the outlet from the tube, and a fusible plug on the bottom of the frame supporting the extinguisher in spaced relation thereto.

6. In a fire-extinguisher, a frame having a bottom and a hinged bail, an extinguisher comprising inner and outer receptacles and a tube extending from the inner receptacle through the wall of the outer receptacle and movable therewith, a fusible plug in the bottom of the frame supporting the outer receptacle in spaced relation thereto and a stopple supported on the bail and adapted to seal the outlet from the tube, said stopple being held against movement with the tube.

7. In a fire-extinguisher, inner and outer receptacles, a tube extending from the inner receptacle through the wall of the outer receptacle and movable therewith, fusible means supporting the outer receptacle and supported means to positively seal the outlet from the tube when the fusible means is intact, said means being held against movement with the tube.

8. A fire extinguisher comprising a recep-

tacle for a fire extinguishing material, a tube extending from said receptacle, fusible means supporting said receptacle and means exerting pressure on the fusible means to positively seal the outlet from the tube while the fusible means is intact.

9. A fire extinguisher comprising a receptacle for a fire extinguishing material, a tube extending from said receptacle, fusible means supporting said receptacle and means exerting pressure on the fusible means to positively seal the outlet from the tube while the fusible means is intact, said means including a spray head.

10. A support for a fire extinguisher embodying a receptacle and closure means therefor, each supported independently of the other, and in which operation is initiated upon movement of said receptacle away from said closure means, comprising a frame and a fusible member thereon upon which the receptacle is adapted to rest.

11. A support for a fire extinguisher embodying a receptacle and closure means therefor, each supported independently of the other, and in which operation is initiated upon movement of said receptacle away from said closure means, comprising a frame having a bottom portion and a supporting bail, and at least one fusible member on the bottom portion upon which the receptacle is adapted to rest.

In testimony whereof I affix my signature.
